UNITED STATES PATENT OFFICE.

WILFRID JEAN, OF LOWELL, MASSACHUSETTS.

AUTOMOBILE HEATER.

1,425,483.

Specification of Letters Patent. Patented Aug. 8, 1922.

Original application filed July 21, 1919, Serial No. 312,190. Divided and this application filed April 23, 1920. Serial No. 376,112.

To all whom it may concern:

Be it known that I, WILFRID JEAN, a citizen of the United States, residing at Lowell, in the county of Middlesex and State of Massachusetts, have invented certain new and useful Improvements in Automobile Heaters; and I do declare the following to be a full, clear, and exact description of the invention, such as will enable others skilled in the art to which it appertains to make and use the same.

My invention relates to improvements in automobile heating devices of the type which utilize the exhaust gases from the engine as a heating means; and the present application is a division of my U. S. application Serial No. 312,190, filed July 21, 1919.

The object of the invention is to provide an extremely simple and inexpensive, yet a highly efficient, durable and reliable heating device which may be accurately controlled so as to heat the car to the desired temperature.

With the foregoing in view, the invention resides in the novel construction of the heater as hereinafter described and claimed, the descriptive matter being supplemented by the accompanying drawings.

Fig. 1 is a horizontal section of a heater constructed in accordance with my invention.

Figs. 2 and 3 are respectively transverse and longitudinal sections cut on the planes indicated by the lines 2—2 and 3—3 of Fig. 1.

In the drawings above briefly described, the numeral 6 designates a shallow sheet metal casing preferably having an outstanding flange 7 at its upper edge, the top of said casing being provided with a grating 8 which may be secured to said flange by bolts or the like 9, and a suitable packing strip 10 is by preference clamped between 40 the grating and the flange.

Located within and spaced from all sides of the casing 6, is a shallow gas-circulating casing 11 which is preferably flanged at its upper edge as at 12 for attachment to a 50 cover plate 13 which may well be secured in place by bolts 14, a suitable packing 15 being provided between the plate and flange as shown. Flanged couplings 16 are riveted or otherwise secured to the bottom of the 55 casing 11 and serve to connect a flexible heat

supply pipe 5 and a flexible exhaust pipe 17 to the heater. One of these pipes communicates with the casing 11 at one corner, and the other at the diagonally opposite corner and suitable baffle plates 18 extend from 60 opposite ends of said casing to force the hot exhaust gases to take a tortuous course, so that they will produce maximum heating efficiency. The flexible pipes 5 and 17 are not secured to the casing 6, being merely 65 passed through openings therein.

For properly supporting the casing 11 within the casing 6, I provide a plurality of hanger bars 19 whose ends are bent upwardly at 20 and then extended laterally 70 outward at 21. The lateral portions of these bars are bolted against the lower side of the grating 8 and may well be clamped between said grating and the flange 7 as shown, and the horizontal intermediate portions of the 75 bars in question may be secured to the casing 11, either by bolts 14 or otherwise. The bars 19 form the sole supporting means for the casing 11.

The front side wall and bottom of the 80 casing 6 are provided with an appropriate number of air inlet openings 22 which may be controlled by suitable dampers 23. By properly positioning these dampers, the amount of cold air entering the casing 6 90 around the exhaust heated casing 11, may be so regulated as to control the temperature of the machine. This controlling may also be effected by directing more or less of the hot exhaust gases through the device, 90 by means of an appropriate valve, which however is not disclosed in the present case since it constitutes the subject matter of another application.

The heater is suitably installed, preferably in the floor of an automobile and the flexible heat supply pipe is connected with the exhaust manifold by the above mentioned valve or other appropriate means. It will thus be seen that the exhaust gases may 100 be directed through the casing 11 and that they will take a tortuous course so that the casing is highly heated. It will thus be seen that the air entering the openings 22 will strike the casing 11 and be raised considerably in temperature, escaping through the grating 8 into the machine, and by properly operating the slides 23, so that more or less fresh air may be admitted, the temperature of the car may be readily controlled. 110

When the use of the heater is not needed, the exhaust gases are allowed to escape directly through the usual exhaust pipe and muffler without shunting through the gas heated device.

By constructing the heater in the novel manner shown and described, it may be easily and inexpensively manufactured and marketed, and may be installed with ease 10 on numerous makes of machines, and on account of these advantages, such details are preferably followed. I wish it understood, however, that within the scope of the invention as claimed, numerous minor changes 15 may well be made.

I claim:

1. An automobile heater comprising a shallow casing having air inlet means, a grating closing the top of said casing, a second and relative small shallow casing located in said first named casing and having an exhaust gas inlet and an outlet, and a 20

plurality of supporting hanger-bars secured to the top of said second casing, the ends of said bars being bent upwardly and laterally and secured against said grating, thereby to secure said second casing in place. 25

2. An automobile heater comprising a shallow casing provided at its upper edge with a lateral flange, a grating secured to said flange, a relatively small shallow casing within said first named casing, a plurality of horizontal bars secured to the upper side of said relatively small casing and bent upwardly at the ends thereof to form supporting arms, the upper ends of said arms being bent laterally outward and secured between said grating and the lateral flange of said first named casing, said relatively small casing having an exhaust gas inlet and an exhaust gas outlet. 30 35

In testimony whereof I have hereunto set my hand.

WILFRID JEAN.
